DESIGN FOR A METALWORKING MACHINE

Artie C. Carlson, Detroit, Mich., assignor, by direct and mesne assignments, to Bremau Corporation, Detroit, Mich., a corporation of Michigan

Application July 18, 1941, Serial No. 102,213

Term of patent 3½ years

To all whom it may concern:

Be it known that I, Artie C. Carlson, a citizen of the United States, residing at Detroit, county of Wayne, and State of Michigan, have invented a new, original, and ornamental Design for a Metal Working Machine, of which the following is a specification, reference being had to the accompanying drawing, forming a part thereof.

In the drawing:

Fig. 1 is a perspective view of the front and one side of a metal working machine showing my new design.

Fig. 2 is an elevation of one side of the machine opposite the side shown in Fig. 1.

I claim:

The ornamental design for a metal working machine, substantially as shown.

ARTIE C. CARLSON.

CERTIFICATE OF CORRECTION.
